attys.

UNITED STATES PATENT OFFICE.

SETH WHITE PAINE, OF ROCHESTER, NEW YORK.

IMPROVEMENT IN SEED-SOWERS.

Specification forming part of Letters Patent No. 125,324, dated April 2, 1872.

To all whom it may concern:

Be it known that I, SETH W. PAINE, of Rochester, in the county of Monroe and in the State of New York, have invented certain new and useful Improvements in Hand Seed-Sowers; and do hereby declare that the following is a full, clear, and exact description thereof, reference being had to the accompanying drawing making a part of this specification, in which—

Figure 1 shows my device when in operation. Fig. 2 is an enlarged side elevation of the same. Fig. 3 is an elevation of its lower end with the sieve-cap removed; and Fig. 4 is a central section of the same, with said sieve-cap in place, on line xx of Fig. 3.

Letters of like name and kind refer to like parts in each of the figures.

My invention is intended for use in the sowing by hand of grain or seed; and it consists principally in the device as a whole, substantially as and for the purpose hereinafter specified. It consists further in the means employed for separating the grain so as to cause them to be evenly distributed over the ground, substantially as is hereinafter set forth. It consists finally in the means employed for securing the sieve-cap to or upon the seed-box, substantially as and for the purpose hereinafter shown and described.

In the annexed drawing, A represents a metal tube, having, preferably, a diameter of about one and one-half inches and a length of one foot, to or upon the lower end of which is secured a metal box, B, having the shape shown in Figs. 3 and 4. The box B is entirely inclosed, except where it is joined to the pipe A and upon its lower side, where, from one end inward about one-third of its length, the lower side b is removed and the opening C thus formed inclosed by means of a corresponding tube, D, which, extending vertically downward, is open at its lower end. The opening C is inclosed, when desired, by means of a slide, E, which rests upon the inner face of the side b , and is moved longitudinally thereon by means of a screw, F, which is swiveled within the ends of the box B, and passes through a threaded opening within said slide, or through a nut secured to or upon the upper side of the same. A head, f , attached to one end of the screw,

enables the same to be rotated and the slide to be adjusted at will over or from the opening C. The open end of the tube D is inclosed by means of a cap, G, constructed of wire-cloth in the form shown, and provided at its upper end with a collar, H, which corresponds to and fits over the outer side of said tube. A spring, I, is fastened at one end to or upon the box B, and, extending downward over the collar H, is provided upon its under side with a stud, i , which fits into a corresponding opening in said collar, and secures the same and said sieve to or in place upon the tube. A suitable bag, K, attached to or upon the upper end of the tube A, and provided with a strap, L, for suspending it from the shoulder of the operator, completes the device, the operation of which is as follows:

The bag is filled with grain and suspended from the shoulder of the operator, as shown in Fig. 1, the tube A grasped by his right hand and the device swung from side to side as he walks forward. The grain, passing downward through the box B, opening C, and tube D, enters the sieve-cap G, where it spreads outward and passes through the meshes g , and falls upon the ground. By a proper adjustment of the valve or slide E the quantity of grain passing outward is regulated, while by graduating the size of the meshes of the sieve-cap a larger or smaller number of grains will be permitted to pass through each, and the grain correspondingly concentrated or scattered.

In order that the position of the slide with relation to the discharge-opening may be known with certainty, a slot, M, corresponding in direction to the motion of said slide, is provided in and through the lower side b of the box B, and permits the outward passage of a stud, e , attached to said slide. A pointer, e' , is secured upon and extends laterally outward from said stud e over a graduated scale, m , formed upon or secured to said side b , and provided with certain lines, which indicate, when said pointer is placed directly over one of the same, the exact distance of the forward end of the slide from the corresponding end of the discharge-pipe.

This device, while simple in construction and costing but little, will enable a person ordinarily skillful to sow grain with as much regu-

larity and with equal rapidity as would be possible with the ordinary power-seeders.

Having thus fully set forth the nature and merits of my invention, what I claim as new is—

1. A hand seed-sower, in which is a bag or equivalent reservoir for grain, a delivery-tube, regulated in size by means of an adjustable slide, and a screw or cap, composed of wire-cloth, for separating and scattering the grains, substantially as is specified.

2. In combination with the delivery-tube D, the cap G, constructed of wire-cloth, in the

form and for the purpose substantially as set forth.

3. In a seed-planter, in combination with the cap G and H, the spring I provided with the stud i, substantially as and for the purpose shown and described.

In testimony that I claim the foregoing I have hereunto set my hand this 5th day of February, 1872.

SETH WHITE PAINÉ.
